UNITED STATES PATENT OFFICE.

LEONARD H. LITSCHER, OF DAYTON, OREGON.

ALARM FOR INCUBATORS.

988,198.

Specification of Letters Patent. Patented Mar. 28, 1911.

Application filed July 28, 1909. Serial No. 510,008.

To all whom it may concern:

Be it known that I, LEONARD H. LITSCHER, a citizen of the United States, residing at Dayton, in the county of Yamhill and State 5 of Oregon, have invented a new and useful Alarm for Incubators, of which the following is a specification.

This invention relates to an alarm adapted for use more especially in connection with 10 incubators, in combination with the thermostatically-actuated damper therefor, whereby the alarm will be actuated when the temperature in the incubator rises or falls to an abnormal point to show that the heating 15 system of the incubator requires attention in order that the attendant can restore normal conditions.

The invention has for one of its objects to provide an electrically-actuated alarm which 20 is in the nature of an attachment capable of being readily applied to incubators already in use, and so designed as to be comparatively simple and inexpensive to manufacture, reliable and efficient in use, and readily attached to the incubator.

Another object of the invention is the provision of an improved circuit closer having 25 separate contacts associated with a movable part of the thermostatically-actuated damper device so that one set of contacts will be closed when the heat rises to a certain point and the other set will close when the temperature falls to a certain point.

With these objects in view and others, as 30 will appear as the description proceeds, the invention comprises the various novel features of construction and arrangement of parts which will be more fully described hereinafter and set forth with particularity 35 in the claims appended hereto.

In the accompanying drawing, which 40 illustrates one embodiment of the invention, Figure 1 is a perspective view of a portion of the incubator showing the alarm attachment applied in co-operative relation with the thermostatically-actuated damper device. Fig. 2 is an enlarged longitudinal section through the circuit closer. Fig. 3 is a sectional view of the circuit closer taken between the base plate and cover thereof. Fig. 4 is a transverse section of the circuit closer, the section being taken on line 4-4, Fig. 3.

Similar reference characters are employed 45 to designate corresponding parts throughout the views.

Referring to the drawing, A designates an incubator of any approved type, such for instance, as that known in the trade as "Old Trusty", which is equipped with a heating lamp 1, a hot air box 2, and a thermostatically-actuated damper device for controlling the temperature, the said device including a movable arm 3 extending out of one end of the incubator and movable by the usual thermostat arranged within the incubator body, the arm being connected by a link 4 with a swinging damper-carrying lever 5.

The attachment comprises a circuit closer B mounted on the incubator body, in co-operative relation with the movable thermostat arm 3, and this circuit closer is connected by binding posts 6 and 7 with the wires 8 and 9, respectively, of a circuit which includes a bell 10 or equivalent signal device and a 75 source of current such as a cell or battery of cells 11, the object of the attachment being to cause the bell to sound when the temperature in the incubator becomes excessively high or low.

The circuit closer comprises a supporting base 12 of wood or other insulating material formed into a base plate *a* and a cover plate *b* between which latter and the base plate are arranged the contacts 13 and 13^a, and 80 14 and 14^a, which project outwardly from one end of the insulating base. The contacts 13 and 13^a are disposed between and normally spaced from the contacts 14 and 14^a and are flexible so that they can be 85 moved into and out of engagement with the contacts 14 and 14^a, which are relatively fixed. The circuit closer is mounted on the incubator in such position that the contacts 13 and 13^a will extend over and under 90 the arm 3 of the thermostatically-actuated damper device, so that as the latter moves upwardly or downwardly, either set of contacts 13 and 14, or 13^a and 14^a will be engaged for closing the circuit. The inner 95 contacts 13 and 13^a are constructed of a single piece of wire of U-shaped form with a central coiled portion 15 for constituting an eye, and the contacts 14 and 14^a are of similar construction but somewhat larger, 100 so that the contacts 13 and 13^a can be arranged within the U-shaped wire forming the contacts 14 and 14^a. The binding posts 6 and 7 are, respectively, connected with 105 the wires and each binding post consists of 110

a screw 16 which passes through the two parts of the insulating base and through the eyes 15. On the outer ends of the screws are washers 17 and clamping nuts 18 whereby the wires 8 and 9 of the alarm circuit can be connected with the binding posts. The inner ends of the screws are formed with heads 19 that are countersunk in the base plate *a* and the inner surface of the cover plate is formed with sockets or recesses 20 for receiving washers 21 which clamp the eyes 15 of the wire contacts against the base plate and also electrically connect the said wires with the screws of the binding posts. These binding posts serve to clamp the two sections of the base plate together, as do also the screws 22 which fasten the circuit closer to the incubator. The inner surface of the cover plate is provided with channels 23 for accommodating the inner doubled portions of the U-shaped wire contacts, so that the two sections *a* and *b* of the insulating support can fit closely against each other. To afford good electrical connection between the relatively yielding and fixed contacts, the outer ends of the wires are flattened, as clearly shown in Figs. 2 and 3, so as to provide a larger contact surface and also to render said extremities more flexible.

During normal operation, the thermostatically actuated damper device will maintain the temperature within the incubator substantially constant and the arm 3 will move back and forth without closing the alarm circuit, but when for any reason the temperature becomes abnormally high or low in the incubator, the excessive movement of the arm 3 will move the contact 13 or 13^a into engagement with the respective coacting contact 14 or 14^a so as to close the alarm circuit and energize the bell. In the first case, the current will flow from the battery through the wire 9, post 7, contact members 13 and 14, which are held in engagement with each other by the arm 3, as shown by dotted lines in Fig. 3, binding post 6, wire 8 and bell 10. In the second case, the current would flow through the contacts 13^a and 14^a to cause the sounding of the bell. The attendant will thus be informed that some abnormal condition exists in the incubator and attention is required to correct the same.

From the foregoing description, taken in connection with the accompanying drawing, the advantages of the construction and of the method of operation will be readily apparent to those skilled in the art to which the invention appertains, and while I have described the principle of operation of the invention, together with the apparatus which I now consider to be the best embodiment thereof, I desire to have it understood that the apparatus shown is merely

illustrative, and that such changes may be made when desired as are within the scope of the claims appended hereto.

Having thus described the invention, what I claim as new, and desire to secure by Letters Patent, is:—

1. In a temperature alarm for incubators, an alarm circuit, a circuit closer therefor comprising an insulating base, a pair of concentrically-arranged normally-separated U-shaped conductors separately secured to the insulating base, a single binding post on the base at the bend of each U-shaped conductor to connect the same with the alarm circuit, and a movable element responding to temperature changes and in the path of which element the extremities of the U-shaped conductors are located, whereby under predetermined conditions the said movable element will cause engagement of the extremities of one U-shaped conductor with the corresponding extremities of the other conductor to thereby close the alarm circuit.

2. In a temperature alarm attachment for incubators, an alarm circuit, a circuit closer therefor comprising an insulating base, a U-shaped wire device mounted on the base to form a pair of contacts, a second U-shaped wire device smaller than the first mentioned device and arranged within the latter to form a pair of contacts, said second U-shaped wire device being rigidly secured to the base and having free extremities, and binding posts connected with the said U-shaped devices and fastened on the insulating base, said attachment being adapted to respond to a movable element lodged between the extremities of the inner U-shaped wire device.

3. A temperature alarm attachment for incubators comprising an alarm circuit, and a circuit closer therefor consisting of an insulating base composed of a pair of separable sections, separate bent wires clamped between said sections in a common plane and having their extremities projecting outwardly therefrom to form resilient inner contacts spaced one from the other and outer contacts spaced from the inner contacts, and means for clamping the sections together constituting binding posts for the wires.

4. In an alarm attachment for incubators, a circuit closer adapted to be included in a suitable alarm circuit, said circuit closer comprising an insulating base composed of separable sections, U-shaped wires having their bent portions clamped between the sections of the base plate and their extremities projecting freely outward from the base plate and normally spaced one from the other, the said free extremities of the wires being flattened to provide extended contacting surfaces, and binding posts secured to the base plate and constituting means for

the inclusion of the circuit closer in an alarm circuit.

5. In a temperature alarm attachment for incubators, a circuit closer adapted to be included in an alarm circuit, said circuit closer comprising an insulating base composed of separate plates, a pair of wires bent into U shape and one larger than the other, said wires being arranged with their bent portions disposed between the plates and having their extremities extending freely beyond the plates in approximately parallelism one to the other and spaced apart, said wires having eyes formed at their bent portions, and binding posts including screws passing through the plates and through the eyes of the wires for holding the latter in place, one of the plates making up the base having channels for receiving the wires.
- 10 6. A circuit closer comprising an insulating supporting base, a pair of U-shaped

wires secured thereto and one larger than the other, said wires being arranged with their outer extremities spaced apart in parallel relation, separate binding posts on the 25 base, one for each wire and for connecting the same with a circuit, the extremities of one of the wires being resilient to move into and out of engagement with the extremities of the other wire, in combination with means 30 for engaging one or the other of the resilient extremities for moving the same into contact with the corresponding extremities of the other wire.

In testimony, that I claim the foregoing as 35 my own, I have hereto affixed my signature in the presence of two witnesses.

LEONARD H. LITSCHER.
